UNITED STATES PATENT OFFICE.

WILLIAM P. BRITAIN AND GEORGE JOHN PACKMAN, OF WESTPLAINS, MISSOURI.

AUTOMATIC FIRE-ALARM.

995,221.

Specification of Letters Patent. Patented June 13, 1911.

Application filed May 7, 1910. Serial No. 520,085.

To all whom it may concern:

Be it known that we, WILLIAM P. BRITAIN and GEORGE JOHN PACKMAN, citizens of the United States, residing at Westplains, in the county of Howell and State of Missouri, have invented certain new and useful Improvements in Automatic Fire-Alarms, of which the following is a specification.

This invention relates to automatic fire alarms of that class in which fusible elements are used to close the electric circuit of alarms and the like.

It has in view the construction of a device of the above nature comprising outer and inner casings or members, to either one of which may be applied an easily fusible conductive metal causing the same to fuse and form a contact between the casings when the temperature outside becomes higher than usual.

With the above and further objects in view this invention consists in the construction, combination, and arrangement of parts all as hereinafter more fully described, specifically claimed, and illustrated in the accompanying drawings, wherein—

Figure 1 illustrates the manner in which the present invention is used; Fig. 2 is a longitudinal cross section of the device; Fig. 3 is a bottom plan view of the outer casing; Fig. 4 is a top plan view of the inner casing; Fig. 5 is a plan view of the insulating material for use with the present invention; Fig. 6 is a cross section of the device.

Referring more particularly to the drawings A indicates an alarm of any nature such as a bell or annunciator having the usual connections to the battery.

The present invention as indicated at B may be connected to the circuit wires at various intervals and preferably in places where fire would likely break out. This device or electric circuit closer B is composed of a plurality of plates or casings 1 and 2. The outer plate 1 comprises a circular piece of metal having a cone center 3 and oppositely extending wings 4 and 5, the wing 4 being of greater length than the wing 5. The inner casing or plate 2 is similarly constructed having a cone center 3' adapted to extend upwardly into the cone 3. Extending radially from the outer plate and extending laterally from the wings 4 and 4' are a plurality of ears 6 adapted to be bent over the opposite casing for retaining the two together. Applied to either cone

center is an easily fusible conductive metal 7 being so applied thereto as to prevent making contact, the plates being spaced apart by means of an insulating material 8. 60 This insulating material has its center cut out permitting the cone 3' to protrude therethrough, and the said material is provided with outwardly extending ears 9 to coincide with those of the plates, the said ears 9 65 serving the purpose of insulating the ears 6 of one plate from the other plate. As illustrated in Fig. 2 the fusible material is applied to the inner facing of the cone 3 or it may be applied to the outer face of 70 the cone 3' or to both as may be desired. This material or metal may be of variable fusing points according to the positioning of the same.

This device may be secured in any position but preferably against a side wall or ceiling, the same making a sure contact of the two plates when the metal fuses. Any suitable means may be used in securing the circuit closer to the wall, as a screw 10 to 80 which also the wires may be secured, said screws piercing the wings 4 and 4'.

Having thus described our invention, what we claim as new is:

1. In an electric circuit closer, the combination of an outer casing provided with a cone center, an inner casing provided with a cone center adapted to project into the first named cone center, a plurality of oppositely extending wings secured to each casing, a plurality of radially extending ears on one casing, a plurality of laterally extending ears on one wing of each casing, an insulating material interposed between said casings, and a fusible compound applied to 95 one cone center for the purpose herein set forth.

2. As an article of manufacture, an electric circuit closer, comprising spaced conducting members having conical portions, the conical portion of one member nesting with the conical portion of the other member, insulating material interposed between said members, fusible metal applied to one member adapted to fuse and complete the 100 electric circuit, and ears provided on one member adapted to bind over on the other member for retaining said members together said ears being insulated from said other member as set forth.

3. As an article of manufacture, an electric circuit closer comprising spaced con-

ducting plates provided with conical portions, the conical portion of one member nesting with the conical portion of the other member, an insulating ring interposed between said plates adjacent to the conical portions, fusible metal applied to one member and adapted to fuse and complete the electric circuit, and ears provided on one plate adapted to bind over the other plate

for retaining the plates together, said ears being insulated from said other plate, as set forth.

WILLIAM P. BRITAIN.
GEORGE JOHN PACKMAN.
